UNITED STATES PATENT OFFICE.

PATRICK KEILT, OF BROOKLYN, NEW YORK.

WATER-SERVICE PLUG.

SPECIFICATION forming part of Letters Patent No. 288,642, dated November 20, 1882.

Application filed September 29, 1882. (No model.)

To all whom it may concern:

Be it known that I, PATRICK KEILT, of the city of Brooklyn, county of Kings, and State of New York, have invented a new and useful Improvement in Water-Service Plugs; and I do hereby declare that the following specification, taken in connection with drawings annexed to and forming part of the same, furnishes a full and clear description of the invention, sufficient to enable those skilled in the art to which it pertains to make and operate the same.

In the drawings, Figure 1 is a view in cross-section of my improved water-service plug; Fig. 2, a view in cross-section of the box inclosing the same. Fig. 3 is a top view of the claw and cover forming the upper part of the box shown in Fig. 2.

The object of my invention is to simplify and cheapen the construction of such apparatus as is usually used for auxiliary water branches—such as street-washers, &c.

In the drawings, A represents the service-pipe, the arrows denoting the direction of the water to the house from the main.

B is a stop-cock, having a hollow ground-key, C, of usual external construction, with the apertures b b, through which the water-supply flows to the house, and from which the water is cut off by turning the key C. This latter is effected by having the hollow pipe D fitted to the upper end of the key and rising to the surface of the ground, where it is provided with a shoulder to receive a wrench or other suitable instrument for turning. This is the ordinary mode of regulating the house-supply, and is not, in its broad features, claimed by me. The key C, however, I make hollow, with its bore narrowest at the part marked a, just above which it widens out, so as to form

a seat, e e, for a compression-valve, E. This valve E is screwed up and down by a rod, F, of well-known construction, which extends to the surface inside of the pipe D. When the valve E is down on its seat e e it is obvious that no water can rise through the hollow key above the seat e e; but its flow to the house through b will be unimpeded unless the whole key C is turned. The valve E is at the foot of a short plug, J, which fits the inside of the tube D, but which is hollow between the points g g and i i, at which points are openings to

communicate with the inside of the pipe D. When the valve E is raised from the seat e e, the water will flow in the direction of the arrows in at g g and out at i i up the pipe D, thus supplying the washer at the street-surface, where I propose to attach a branch, G, for the attachment of a hose.

The valve-plug J is constructed to fit closely to the inside of the pipe D at the portion h, which forms a shoulder. An aperture, k, through the key C, is made at a point just above where the shoulder h comes when the valve E is down on its seat, thus allowing the water standing in the pipe D to drain off when the supply is cut off from the street-washer. By this means it will be seen the one stop-cock B controls the supply in both directions and saves the expense of an additional cock.

The upper part of the tube D, I secure by passing it through an aperture, m, in a claw, L. This claw is shown in Figs. 2 and 3, and it serves a double purpose. By means of threads N upon its lower portion, or any other suitable means, an attachment is furnished for the box or tube P, which incloses the pipe D, to protect it from the earth, if below the ground, or from other injury if above the ground, while upon its upper surface or within the claw L a resting place is furnished for the cover S, which furnishes access to the adjustment of the cocks. This cover S consists of four sides and a lid, and is fastened to the claw L by screws through the holes in the claw at w w, thus enabling an easy removal and substitution of the cover S (in case of the breakage of covers which is so common) without the expense or trouble of renewing any of the parts of the box P below the cover S. Upon the claw L, I place two pins, t t, as shown in Fig. 3.

Y is a stop fastened to the upper part of the pipe D, of substantially the shape shown in Fig. 3. This stop may serve as a support for the pipe D upon the claw L; but on one side of this stop the edge is so shaped as to form bearings y y, which will, as the pipe is turned from right to left, come in contact with the pins t t, respectively, and limit the rotary motion of the pipe D at just the points required to let the water-supply to or cut it off from the apertures b b.

The device which I have hereinbefore de-

scribed contains many features which, by themselves, or in other combinations, are not new, and contains combinations which may be useful in hydrants and situations other than a simple street-washer; but that portion of my invention which is particularly valuable in a street-washer is the claw L, hereinbefore described.

Having thus described my improved water-service plug, I do not claim, broadly, to be the inventor of a compression-valve for a street-washer, nor for an escape for waste-water; nor do I claim, broadly, the combination of a lid

or cover combined with an upright pipe in a street-washer; but

What I claim as my invention, and desire to secure by Letters Patent, is—

The combination of an upright pipe, D, of a street-washer with an adjustable claw, L, constructed substantially as described, and the removable cover S supported by said claw, substantially as and for the purposes described.

PATRICK KEILT.
